Herman Moskowitz

Inventor

UNITED STATES PATENT OFFICE.

HERMAN MOSCHCOWITZ, OF NEW YORK, N. Y.

FORM FOR PRESERVING AND DISPLAYING WAISTS AND OTHER GARMENTS.

1,156,246.

Specification of Letters Patent.

Patented Oct. 12, 1915.

Application filed December 23, 1914. Serial No. 878,740.

To all whom it may concern:

Be it known that I, HERMAN MOSCHCOWITZ, a citizen of the United States, and residing in the borough of Manhattan, city, county, and State of New York, have invented certain new and useful Improvements in Forms for Preserving and Displaying Waists and other Garments, of which the following is a specification.

10 The object of my invention is to provide a suitable form to preserve in their proper shape and free from wrinkles waists and garments and which form can be adopted for purposes of displaying the waist or garment.

15 In my former application, Serial No. 863,496, filed September 25, 1914, I described my improvement for hanging and displaying garments and means for changing the form for hanging into a form for displaying the garment and means for changing the form for display back to a simple hanging device.

20 My present invention is to provide means more particularly adapted to preserve garments that are packed in boxes for purposes of shipment or storage, especially waists and at the same time provide means for displaying the garment which will not interfere 25 with its use as a form for purposes of packing.

25 My device is preferably made of cardboard, although I am aware that other material can be used, and is adapted to be 30 changed from its function as a packing device not only by operation of the hook as in my previous application Serial No. 863,496, but also by the hands of the person displaying the garment and is further adapted to 35 stand on a counter or table as a figure for display, as will more fully be seen by reference to the drawings herein. My device 40 may also be attached by any suitable means to the bottom of a box for the purpose of holding the garment firmly during shipment, and when the lid is removed the garment 45 may also be advantageously displayed without taking the garment from the box.

It is sometimes desirable to pack waists

of the more expensive kind in separate boxes, 50 and it is now customary in the art to use paper and other materials to fill out the waist, to some extent, in shipment, and for the time that it remains in the box.

55 I insert in my invention a spring which will support the bust forms and thus support the waist when laid flat in a box, and when the spring is not needed for such purposes it can be held against the back member by a clip, as shown and described.

60 Referring to the drawings, Figure I is a front view of my improvement in the form adapted for purposes of packing, the means for displaying the bust portion folding snugly against the back element. Fig. II 65 is a side view of my improvement and shows the device extended for purposes of display and capable of standing on a counter or table.

70 To the back piece A is attached the bust form B' B², B³ flexible at the point B³. The supporting device C is attached to the back piece A and to the bust form B' B² B³, and is flexible at the point C' so as to fold and lie flat against the back piece A. The 75 hook E is devised to operate in the slot E' formed by the back part A and the upper part of the bust form B which is attached to the back part A. The cord D is attached to the hook E and the lower member C and 80 is adapted to extend the bust form B' B² B³ but this can more readily be done with the hands by pressing up the part C. The spring G is anchored to the back part A, and when released from the clip G' will 85 support the bust form B' B² B³ in position when the form is laid flat in a box or otherwise, or when not needed for such purpose is held securely against the back member A by the clip G'. The clip F holds the hook 90 E in its proper place on the back member A.

Having described my invention, what I claim is:

95 In an improvement of the kind described, a back member shaped to display and preserve the form of a garment, a bust form capable of folding against the back member or extending therefrom, with means for ex-

tending and supporting said bust form, comprising a supporting member flexibly attached to the back member and to the bust form and also capable of folding against the part A, and a spring capable of supporting and maintaining the bust form in position and of folding against the back member

and means for securing the spring to the back part, substantially as described.

HERMAN MOSCHCOWITZ.
